UNITED STATES PATENT OFFICE.

ERIC HUGO NELSON, OF MASSILLON, OHIO, ASSIGNOR TO THE GRISCOM-RUSSELL COMPANY, OF NEW YORK, N. Y., A CORPORATION OF DELAWARE.

FUEL-OIL HEATER.

Application filed June 30, 1926. Serial No. 119,546.

The present invention relates to heat-exchanging apparatus in general and resides in certain improvements on the fuel-oil heater disclosed in my copending application, Serial No. 30,224, filed May 14, 1925.

In certain fields of heat power engineering such as in naval or marine service, it is important that all joints in the shell construction of fuel-oil heaters be riveted, and 10 in addition, that no welded joints be exposed anywhere on the exterior surface of the apparatus. For this reason, the heater specifically described in that application is not acceptable for such use, notwithstanding the 15 fact that otherwise the heater is highly successful and desirable.

The principal object of the present invention is to obviate the external welded joints in the heater of my copending application 20 without sacrificing any of the advantages of that construction thereby.

The invention will be further described in connection with the accompanying drawings, which show the embodiment chosen to 25 be herein disclosed. It is to be understood, however, that these drawings and the subsequent description thereof are only for the purpose of illustrating one typical form of the present invention, and the invention does 30 not lie solely in the drawings and is not confined thereto. In these drawings,

Fig. 1 is a vertical, central sectional view of a fuel-oil heater embodying the present invention;

Fig. 2 is a top plan view of the fuel-oil heater;

Fig. 3 is a section along line 3—3 of Fig. 1, sighting in the direction of the arrows;

Fig. 4 is a detail view of the joint of the 40 present invention as embodied in the upper part of the fuel-oil heater; and

Fig. 5 is a detail view of the joint of the present invention as embodied in the lower part of the fuel-oil heater.

Referring now more in detail to the drawings by numeral, the improved heater comprises a shell 1, preferably having riveted seams, (not shown) and surrounding a bundle of heat-transferring tubes 2, which 50 extend longitudinally of the shell 1 and constitute the heat-transferring surface of the apparatus, which is in general constructed according to the principle of my copending application referred to above.

The shell 1 has a flange 15 at one end,

preferably riveted thereto, for the reason that the heater is particularly intended for use as a naval or marine-type heater. At the other end of the shell, a somewhat similar flange 15' is also riveted thereto. These 60 flanges are so made, either by casting, forging, or machining, that they constitute means for accommodating the usual unequal expansion and contraction between the tubes and the shell. The flanges are each constructed as an essentially separate annulus, having a kerf or annular groove in the interior surface of the horizontally extending part in the place and manner shown, thus forming an annular lip 14', in the place 65 shown, and possessing a sufficient degree of flexibility to absorb and accommodate relative longitudinal expansion and contraction between the tubes and the shell. The part by which the flange is directly riveted to 70 the shell is cast, or forged and bent, to form a collar, as shown, integral with the rest of the flange.

In order to obviate all exterior welds in the fuel-oil heater, the tube sheets 3 and 4 80 are shaped and extended as shown in Figs. 4 and 5 to form annular tongues 13 which fit into complementary recesses in the edge of the inner periphery of the flanges 15 and 15', which are riveted to the shell 1, and 85 the tube sheets are joined to the flanges on the interior of the ring of bolts 20, as at 22, by any suitable means.

These flanges or expansion absorbers, are 90 the same in principle and operation as those disclosed in my copending application. They are each constructed, as explained, as an essentially separate annulus, with a kerf or annular groove in the interior surface in such a place and of such a size as to form 95 an annular lip possessing a sufficient degree of flexibility to absorb and accommodate relative longitudinal expansion and contraction between the tubes and the shell.

The caps or heads 6 and 8 are bolted down 100 onto the outer faces of the flanges or expansion rings 15 and 15' over the tongue 13 of the tube sheets by the ring of bolts 20. A fluid-tight connection between the flanges 15 and 15', the shell 1, and the tube sheets 3 and 4 is then established as shown, without necessitating any exterior welded joints at all thereby, as the surface of contact between the tube sheet and the absorbing flanges can quite satisfactorily be gasketed 110

or packed, instead of welded. The under lip 14 of the flange 15 prevents the tube sheet 3 from dropping into the shell, if it is not otherwise secured.

5 If preferred, however, a weld or braze can be substituted for packing at this surface of contact 22 between the tube-sheets and the flanges. The best forms of welds are the triangular welds shown at 22 in
10 Figs. 1, 4 and 5. These welds are provided, however, solely to preserve fluid-tightness between the heads, the tube sheets, and the flanges.

These preferred weld seams or brazes, 15 however, are never subjected to any fluid pressure of any kind, inasmuch as they are protected by the caps or heads 6 and 8 and the flanges 15 and 15', as will be understood from Figs. 4 and 5, and this is the reason
20 why they can be quite satisfactorily replaced by gaskets or packings, as suggested.

The tube sheet 4, at the other end of the shell, is secured to the flange 15' and the shell in the same way as the sheet 3, and in
25 addition, may be provided with a drain plug 16 which drains the space 17 by means of the passage 18.

Oil enters the apparatus through the inlet opening 5 provided in the end-closure, head, 30 or upper cap 6 of the apparatus, which is bolted to the top of the flange 15, as shown in Figs. 2 and 4, and in a similar manner, cap 8 is bolted to flange ring 15'. The oil passes through the interior of the heat transfer tubes 2 and issues through the outlet opening 7, also in upper cap 6, as shown in Fig. 2. In the arrangement here shown, a 4-pass construction is employed, the operation of which in directing the flow of the oil
40 throughout the successive groups of tubes is clearly shown in the drawings, but does not constitute a principal object of the present invention, and is therefore not described in detail.

45 Heating steam is admitted to the shell 1 through the inlet opening 9 and circulates about in the shell, coming into direct contact with the exterior surfaces of the heat transferring tubes 2. The condensate drains out
50 through the outlet 10 provided for that purpose. A baffle-plate 11 is also provided for the purpose of causing a uniform distribution of the steam upon its entering the shell.

Hence the shell with the tube sheets at its
55 respective ends and the tubes extending between the tube sheets constitute an essentially fluid-tight heat exchange unit without any exterior welded joints. The end-closures, heads, or caps, 6 and 8 may be secured
60 to the flanges 15 and 15' in any desired fashion, as, for instance, by bolting them together. In the embodiment here shown, the flanges 15 and 15' are provided with studs
65 secured in the rings. The heads or caps 6 and 8 are provided with corresponding

flanges 19 and 19' having in them a series of bolt holes which fit over the respective studs 20. Connection between the parts is established by screwing down the nuts 21 upon the upper threaded portions of the studs 20.

I have described my invention as combined with a heat exchange apparatus of the species disclosed in my co-pending application, but it is to be understood from the foregoing description and explanation that my invention is also combinable with any heat exchange apparatus consisting of two headers, a shell, two tube sheets and a nest of tubes, and in the resulting heat-exchanger there are no obligatory welded joints at all and no external welded joints whatsoever. The optional internal welded joint is never subjected to direct fluid pressure of any kind, and thus the apparatus is adapted to exceedingly high pressure and high temperature duty. The separate flanges connecting the heads, tube sheets and shell are simple beyond expectation to construct, as it is an easier mechanical operation to kerf a groove in a separate, flat annulus made according to the present invention than to kerf the necessary expansion space in a single piece including the tube sheets integral therewith.

I claim:

1. A heat exchanger comprising a shell, a bundle of tubes therein, a tube sheet at the end of the shell having an annular tongue on its periphery, a head over the tube sheet, and a flange-like member lying completely outside of and surrounding said shell between said head and the shell end, said member comprising an essentially flat annulus of slightly larger diameter than the shell and having a collar formed on its shell-end face to fit over the end of the shell, the inner edge of said annulus having an annular groove therein extending radially thereof a sufficient distance to divide the upper and lower portions of said edge into upper and lower annular lips, the upper lip having an annular recess in the head-side face thereof to receive the annular tongue on said tube sheet, and the lower lip being connected to the shell by said collar.

2. Heat-exchange apparatus of the class described, comprising a containing shell, heat transfer tubes within the shell, a tube-sheet, said tube-sheet having an annular tongue on its periphery, a head forming with the tube-sheet a chamber for distributing fluid to the tubes, and a flange associated with said shell and said tube-sheet between the head and the shell-end, said flange being of essentially flat annular configuration surrounding the shell-end and extending parallel to the tubes from the shell-end to the end of the tubes, said flange having a laterally-extending groove starting on its tube-side edge, said groove forming an annular lip on the head-side of said flange, and an annular lip on the

shell-side of said flange, said head-side lip having an annular recess in the outer edge thereof to receive the tongue on said tube-sheet, the shell-side lip having a bend there-in at right-angles to the annulus for slipping over the shell-end and attaching thereto.

3. A heat exchanger comprising a shell having a bundle of tubes therein, a tube sheet at the end of the shell having an annular tongue on its periphery, a flange-like member surrounding the shell and having its greater portion lying completely outside of the shell, said member comprising an essentially flat annulus, the inner edge of which 15 has an annular groove therein extending ra-

dially thereof a sufficient distance to divide the upper and lower portions of said edge into upper and lower annular lips, the lower lip being connected to the shell and the upper lip having an annular recess in the outer face thereof to receive the annular tongue on said tube sheet, and a head forming with the tube sheet a chamber for distributing fluid to the tubes, said head having a flat annular clamping face extending over said annular tongue on the tube sheet, and means for clamping said head to said flange-like member.

In testimony whereof I affix my signature.
ERIC HUGO NELSON.
